CLAIM

The ornamental design for a focusing wheel for binoculars, as shown and described.

DESCRIPTION

FIG. 1 is a perspective view of a focusing wheel for binoculars showing my new design;

FIG. 2 is a front elevational view of the binoculars;

FIG. 3 is a right side elevational view thereof;

FIG. 4 is a top plan view of the focusing wheel for binoculars;

FIG. 5 is a left side elevational view thereof;

FIG. 6 is a rear elevational view thereof; and,

FIG. 7 is a bottom plan view thereof.

The components of the binoculars shown in broken lines are for illustrative purposes only and form no part of the claimed design.

The surface(s) or portion(s) of the article not shown in the drawing or described in the specification form(s) no part of the claimed design.
